SPRAY NOZZLE

David Bendersky and Frank H. Gage, Kansas City,
and Wallace M. Yoeum, Independence, Mo., as-
signors, by mesne assignments, to Viking Cor-
poration, Hastings, Mich., a corporation of
Michigan

Application May 14, 1949, Serial No. 93,394

12 Claims. (Cl. 299—114)

1

This invention relates to new and useful im-
provements in spray nozzles, and more particu-
larly, to spray nozzles adapted to control and ex-
tinguish fires through fixed installations.

It is well known that fires in general and cer-
tain kinds of fires in particular may be more ef-
fectively combated and extinguished by the use
of water or other liquids in the form of a conical
spray of rather large droplets of liquid distributed
throughout the spray and traveling with suf-
ficient velocity to penetrate the updraft caused by
the fire, than by a solid stream of water or by
the use of a finely divided spray in the form of a
fog.

In fighting fires through fixed installations, the
area that can be covered by the spray is in most
instances larger than can be covered by one
nozzle. In such instances, several nozzles are
used and are so spaced as to cover the required
area with the spray.

Where, however, the surface to be protected is
sufficiently small to be covered by the spray from
one fixed nozzle, it is desirable that the nozzle
produce a solid cone of spray with the droplets
of liquid uniformly distributed throughout the
entire spray pattern.

Where the complete area cannot be covered by
one spray, the edges of the adjacent sprays must
overlap so as to obtain complete coverage. In
these installations, it is desirable that the spray
from each nozzle be heavier in and around the
center of the spray than at the edges thereof, so
that a uniform coverage of the protected area
may be obtained. Also, in order to cover the
greatest possible area with a single nozzle and to
minimize the number of nozzles necessary to pro-
tect a given surface, it is desirable that the angle
of the spray cone be as large as possible, com-
mensurate with sufficient projection to reach the
surface required.

For the spray to be effective under various
pressure conditions, it is also necessary that the
spray nozzle operate satisfactorily over a wide
range of pressures, with no material difference
in distribution of the droplets of liquid for these
various pressures.

It is also desirable that the nozzle be free from
the inserts heretofore used to produce the desired
spray pattern, and that all of the nozzle passages
and orifices be greater than one-quarter inch in
diameter, to make unnecessary the use of strainers
to collect foreign matter which may be in the
water supply system, as required by the rules
governing fixed fire extinguisher installations.

A principal object of our invention is to provide

2

a novel and improved form of spray nozzle which
will produce a conical spray of droplets of liquid
projected with sufficient velocity to penetrate the
heat updrafts of a fire, and having a sufficient
spray angle to cover a relatively large area.

A further object of our invention is to provide
a new and improved spray nozzle arranged to
produce a spray in the form of a relatively wide-
angled cone of spray droplets by the interaction
of two streams of liquid within the body of the
nozzle.

Another object of our invention is to provide a
novel and efficient spray nozzle arranged to pro-
duce a solid cone of spray droplets of liquid uni-
formly distributed throughout the spray pattern.

A still further object of our invention is to pro-
vide a method of distributing liquid in the form of
relatively large droplets throughout a wide-
angled conical spray by creating a pressure dif-
ferential in a flowing stream of liquid and pro-
ducing a rotating jet from the high pressure side
of said pressure differential and a non-rotating
jet from the low pressure side of said pressure
differential, and in directing the non-rotating jet
through the rotating jet.

A more specific object of our invention is to
provide a new and improved form of spray nozzle
which eliminates the use of inserts in the nozzle
and enables the nozzle passageways to be large
enough to be non-clogging by directing a jet of
liquid in a rotating path, directing another jet
of liquid supplied from a common inlet to said
rotating jet in a straight line path through said
rotating jet and along the axis of rotation there-
of, and by discharging the two jets through a
common outlet orifice aligned with the path of
the straight line jet.

A still further object of our invention is to
provide a liquid nozzle having a hollow cylindri-
cal chamber, with an inlet into said chamber di-
recting liquid tangentially of the wall thereof,
another inlet into one end of said chamber di-
recting liquid in a straight line path axially of
the wall thereof, and a liquid diversion passage-
way arranged to divert liquid flowing to the
tangential inlet in such a manner as to create
a pressure differential between the liquid enter-
ing the chamber through the axial inlet and the
liquid flowing through the tangential inlet, with
the pressure of the liquid flowing through the
tangential inlet greater than that of the liquid
flowing through the axial inlet.

A further specific object of our invention is
to provide a spray nozzle having a hollow cylin-
drical chamber with a straight line inlet into

said chamber from one end thereof, a tangential inlet leading tangentially into said chamber, and a simple and novel means for balancing the whirling liquid entering through said tangential inlet.

These and other objects of our invention will appear from time to time as the following specification proceeds, and with reference to the accompanying drawings, wherein:

Figure 1 is a plan view of one form of nozzle constructed in accordance with our invention;

Figure 2 is a sectional view of the nozzle shown in Figure 1, taken substantially along line II—II of Figure 3;

Figure 3 is a sectional view taken substantially along line III—III of Figure 1;

Figure 4 is a horizontal sectional view taken through a modified form of nozzle constructed in accordance with our invention;

Figure 5 is a vertical sectional view of the nozzle shown in Figure 4 and taken along line V—V of Figure 4;

Figure 6 is a plan view of still another form of nozzle construction in accordance with our invention; and

Figure 7 is a sectional view taken substantially along line VII—VII of Figure 6.

Referring now in particular to the form of our invention illustrated in Figures 1 to 3 of the drawings, the nozzle shown therein comprises a body 10 having a hollow cylindrical chamber 11 formed therein, with a threaded inlet portion 12 extending therefrom in a direction perpendicular to a longitudinal axis of said chamber. The chamber, as herein shown, opens from one end of said body and the open end thereof is shown as being of a larger diameter than the inside diameter of said chamber, and as being threaded to receive a threaded end member 14 having a central opening forming a diverging conical outlet orifice 15 of the nozzle. The inside of the member 14 has a cylindrical wall 16 in alignment with and forming a part of the wall of the chamber 11 and has a conical inlet section converging therefrom to the diverging conical outlet orifice 15.

It is apparent that the angle of the outlet orifice may vary to change the spray angle, where desired, by the substitution of different end members having different outlet orifices from the one shown herein.

The inner end of said member 14 is beveled toward the inner edge thereof, as indicated by reference numeral 17. The beveled end 17 is adapted to engage a similarly inclined surface leading from the cylindrical portion of the chamber 11 to the threaded portion thereof to form a seal between the chamber 11 and said end member 14.

An inlet passageway 19 leads through the inlet portion and may discharge tangentially of the wall of the chamber 11 through a groove 20 formed in the wall of said chamber, and extending therealong for a part of the circumference thereof as shown in Figure 2. As herein shown, said groove extends around the wall of said chamber for at least 180° and serves as a balancing groove to obtain a balanced condition of the whirling stream of liquid entering the chamber 11 through the inlet passage 19. This balancing groove gives the same effect as if two tangential inlets, spaced 180° apart, were provided in said chamber. Thus, half of the liquid entering said chamber through the tangential inlet follows the groove 20 around to the opposite side of said

chamber, where it is then projected into said chamber. The other half of the tangential stream of liquid is projected into said chamber as it enters said chamber.

In order to avoid the formation of a hollow cone of spray and to provide a conical spray with droplets of liquid distributed throughout the spray, we provide an inlet 21 entering the opposite end of the chamber 11 from the outlet orifice 15, and in alignment with said orifice. This last mentioned inlet directs a rectilinear stream of liquid axially of said chamber, which interacts with the whirling jet of liquid within said chamber, to produce a solid cone of spray leaving the discharge orifice 15. A liquid diverting passageway 22 leads from a wall of the inlet passageway 19 to supply liquid under pressure to the passageway 21 at a lower pressure than the pressure of the liquid supplied tangentially of the chamber 11, as will hereinafter more clearly appear as this specification proceeds. Said passageway 22 is formed by drilling through the block 18 into the passageway 19, and by drilling through said block into said axial inlet 21 in a direction parallel to said passageway 19, and by closing the outer ends of said drilled passageways by threaded plugs 24 and 25, respectively.

As shown in Figure 3, the liquid diverting passageway 22 is perpendicular to the wall of the inlet passageway 19, although it may leave said wall of said inlet passageway in an angular direction with respect thereto, as shown in Figures 4 to 7. It has been found that where the diversion passageway leaves the inlet passageway at substantially right angles to the wall of said inlet passageway, a more uniform distribution of liquid droplets will be attained throughout the spray pattern than if said diversion passageway leaves said inlet passageway at an angle to the wall thereof. Where the diversion passageway leaves the inlet passageway at an angle to the wall thereof, as in Figures 4 to 7, the spray droplets are more heavily distributed in the center of the spray than at the edges thereof, such nozzles being suitable for use where it is necessary to use a plurality of fixed nozzles in order to adequately cover the area requiring protection.

When the threaded inlet portion 12 is connected to a pressure pipe or other source of supply of liquid under pressure, a portion of the liquid entering the nozzle through the common inlet 19 will be diverted through the diversion passageway 22 and will enter the nozzle through the axial inlet 21, while the rest of the liquid will enter the chamber 11 in a direction tangential to the wall thereof, at a higher pressure than the pressure of the liquid entering through said axial inlet. This pressure differential is obtained by reason of the fact that the liquid entering the chamber 11 through the common inlet 19 contains two forces, one being a static force due to the confinement of the liquid within said passageway, the other being the dynamic force of the liquid flowing through the passageway, due to its velocity of flow therethrough. Since the velocity of a stream of liquid flowing in an enclosed passageway is at a maximum at the center of the passageway, and is zero at the walls of the passageway, the dynamic force of the liquid due to its velocity is also maximum at the center of the passageway and zero at the walls of the passageway. This is taken advantage of by connecting the diversion inlet 22 into the wall of the common inlet 19, so that the static forces of the liquid entering said inlet 19 will act to propel the

liquid into said diversion inlet 22. The liquid discharged tangentially of the wall of the chamber 11 will enter said chamber through the discharge end of the common inlet 19, so that both the dynamic and static forces of the liquid in the common inlet will act to propel the liquid tangentially of the walls of said chamber. The liquid entering the chamber tangentially of its walls will thus be at a higher pressure than the liquid entering the chamber axially of its walls.

Therefore, the liquid entering the chamber 11 in a straight line path in the direction of its axis, and at a lower pressure than the liquid entering said chamber tangentially of its walls, will interact with the swirling liquid entering said chamber from the tangential inlet. This will result in the discharge of a cone spray of liquid of relatively large droplets through the orifice 15 of a much wider spray angle than has heretofore been considered possible with a more uniform distribution of droplets throughout the spray pattern than has heretofore been attained, where the diversion passageway leaves the wall of the common inlet at substantially right angles with respect thereto, as illustrated in Figures 1 to 3.

In the form of our invention shown in Figures 4 and 5, the nozzle illustrated is similar to that shown in Figures 1 and 2 and 3, so the same reference characters are applied to similar parts. In Figure 5, a diversion passageway 23 is shown as leading from a wall of an inlet passageway 24 at an obtuse angle to said wall, and as communicating with the axial inlet 21. In this arrangement of said diversion passageway, the pressure of the liquid entering the axial inlet 21 will be greater than the pressure of liquid entering said inlet in the form shown in Figure 3, but will still be less than the pressure of the liquid entering the chamber 11 tangentially of the wall thereof. This will result in a spray of relatively large droplets of liquid, concentrated more heavily in the center of the circular cross-section of the spray cone than at its edges. Such a spray is of particular advantage where a number of nozzles are spaced uniformly to cover a relatively large area with spray and the sprays overlap at their edges.

In this form of nozzle, the inlet passageway 24 is reduced in diameter at the tangential discharge opening of the chamber 11, forming a shoulder or ridge 25 in said passageway at the point of discharge. This shoulder or ridge causes an increase in the pressure of the liquid in said inlet passageway 24, with the result that an increased amount of liquid enters the chamber 11 through the axial inlet 21 than if said shoulder were absent, as in the form of our invention shown in Figure 3. By varying the diameter of the inlet passageway 24 and thus varying the width of the shoulder 25, a rather fine adjustment of the pressure differential between the axial and the tangential inlets may be obtained. The particular pressure ratio necessary for proper operation under various conditions of coverage and spacing of the nozzles may thus be assured.

In the form of our invention illustrated in Figures 6 and 7, a diversion passageway 26 is shown as leading from a common inlet passageway 27 into the nozzle chamber, at a relatively flat angle with respect to said inlet passageway. It is obvious that with this form of diversion passageway, the pressure of the liquid flowing therethrough will be greater than the pressure of the liquid flowing through the passageway 23 in the

form of our invention shown in Figure 5, assuming that the pressures entering the common inlets are the same in both forms and that the common inlets and tangential inlets are of the same diameter. This increased pressure in the passageway 26 will result in a decrease in the difference in pressures between the liquid entering the chamber 11 through the axial and tangential inlets, and a change in the spray pattern of the nozzle, from the form of nozzles illustrated in Figures 1 to 5, inclusive.

It will be seen from the foregoing that a novel form of spray nozzle, particularly adapted to control and extinguish fires through fixed installations, has been provided, and that this nozzle may be arranged to produce either a conical spray of droplets uniformly distributed throughout the entire spray pattern, or a spray of droplets of liquid more heavily concentrated toward the center of the spray than at its edges.

It may further be seen that these sprays may be obtained without the use of inserts in the nozzle, by taking advantage of the differential in pressure in the stream of flowing liquid, and by creating a swirling motion to the liquid taken from the high pressure side of the stream, and directing liquid from the low pressure side of the stream axially of the swirling stream of liquid, and discharging the two streams through a common restricted orifice.

It will likewise be seen that with the construction of the nozzle just described, all of the passageways through the nozzle and the conical outlet orifice leading therefrom may be relatively large (one-quarter inch and over), so as not to clog, thus rendering unnecessary the use of strainers.

While we have herein shown and described several forms in which our invention may be embodied, we wish it to be understood that we do not wish to be construed as limiting ourselves to the specific forms shown, excepting as expressly limited by the appended claims.

We claim as our invention:

1. A spray nozzle of the class described, having a body, a chamber therein having a circular wall, a liquid passageway in said body leading to said chamber and discharging thereto tangentially of said circular wall, an outlet orifice from one end of said chamber, a second inlet passageway to said chamber discharging into the end thereof opposite from said outlet orifice, and a diversion passageway in said body leading from said liquid passageway transversely of said passageway and communicating with said second inlet passageway and diverting liquid from said first liquid passageway by the static pressure of the liquid flowing through said first liquid passageway.

2. A spray nozzle of the class described having a body, a cylindrical chamber within said body, a tangential inlet to said chamber arranged to discharge liquid thereto tangentially of the wall thereof, an axial inlet entering one end of said chamber, a liquid passageway through said body leading to said tangential inlet, a liquid diversion passageway leading from said liquid passageway transversely of said passageway and communicating with said axial inlet for supplying liquid to said chamber at a pressure lower than the pressure of the liquid supplied through said tangential inlet by virtue of the static pressure of the liquid flowing through said liquid passageway, and a common restricted orifice leading from the opposite end of said chamber from said axial inlet.

3. A spray nozzle of the class described having a body, a cylindrical chamber within said body, a tangential inlet to said chamber arranged to discharge liquid thereinto tangentially of the wall thereof, an axial inlet through one end of said chamber, a liquid passageway through said body leading to said tangential inlet, a liquid diversion passageway leading from said liquid passageway transversely of said passageway and communicating with said axial inlet for supplying liquid to said chamber through said axial inlet at a pressure lower than the pressure of the liquid supplied through said tangential inlet by virtue of the static pressure of the liquid flowing through said liquid passageway, and a common outlet orifice leading from said chamber in alignment with said axial inlet, said outlet orifice having a conical inlet section converging from the cylindrical wall of said chamber and a diverging conical outlet section.

4. A spray nozzle of the class described having a body, a cylindrical chamber within said body, a tangential inlet to said chamber arranged to discharge liquid thereinto tangentially of the wall thereof, an axial inlet into one end of said chamber, a liquid passageway through said body leading to said tangential inlet, a liquid diversion passageway in said body leading from said liquid passageway in a direction transversely of the longitudinal axis thereof and arranged to supply liquid through said axial inlet at a pressure lower than the pressure of the liquid entering said chamber through said tangential inlet by virtue of the static pressure of liquid flowing through said liquid passageway, and a common restricted outlet orifice leading from said chamber in alignment with said axial inlet.

5. A spray nozzle of the class described having a body, a cylindrical chamber within said body, a tangential inlet to said chamber arranged to discharge liquid thereinto tangentially of the wall thereof, an axial inlet into one end of said chamber, a liquid passageway through said body leading to said tangential inlet, a liquid diversion passageway in said body leading from said inlet passageway in a direction perpendicular to the longitudinal axis thereof and communicating with said axial inlet for supplying liquid through said axial inlet at a pressure lower than the pressure of the liquid entering said chamber through said tangential inlet by virtue of the static pressure of liquid flowing through said liquid passageway, and a common outlet orifice leading from the end of said chamber opposite said axial inlet.

6. A spray nozzle of the class described having a body, a chamber within said body having a cylindrical wall, an axial inlet adjacent one end of said chamber, a discharge orifice leading from the opposite end of said chamber, a tangential inlet entering said chamber along the wall thereof and including a flow-balancing groove recessed within the wall of said chamber forming a partial continuation of said inlet and extending around said chamber for at least 180° of its circumference, a liquid passageway in said body leading to said tangential inlet, a diversion passageway leading from a wall of said liquid passageway and extending transversely of the longitudinal axis thereof, said diversion passageway communicating with said axial inlet and being so constructed and arranged as to supply to said chamber liquid at a lower pressure than the pressure of the liquid supplied through said tangential inlet, and an outlet orifice from the opposite end of said chamber from said axial inlet.

7. A spray nozzle of the class described having a body, a chamber within said body having a cylindrical wall, an axial inlet adjacent one end of said chamber, a discharge orifice leading from the opposite end of said chamber, a flow-balancing groove in the wall of said chamber arcuate in cross-section and extending therearound for at least 180° of the circumference thereof, a tangential inlet to said chamber at one end of said groove, a liquid passageway in said body leading to said tangential inlet, a diversion passageway leading from a wall of said liquid passageway and extending transversely of the longitudinal axis thereof, said diversion passageway communicating with said axial inlet and being so constructed and arranged as to supply liquid thereto at a pressure lower than the pressure of liquid supplied through said tangential inlet, and an outlet orifice from the opposite end of said chamber from said axial inlet, said outlet orifice being in alignment with said axial inlet and being of diverging conical form.

8. A spray nozzle of the class described having a body, a chamber within said body having a cylindrical wall, an axial inlet adjacent one end of said chamber, a discharge orifice leading from the opposite end of said chamber, a flow-balancing groove in the wall of said chamber arcuate in cross-section and extending therearound for at least 180° of the circumference thereof, a tangential inlet leading into said chamber at one end of said groove, a liquid passageway in said body leading to said tangential inlet, a diversion passageway leading from a wall of said liquid passageway and extending transversely of the longitudinal axis thereof, said diversion passageway communicating with said axial inlet and being so constructed and arranged as to supply liquid thereto at a pressure lower than the pressure of liquid supplied through said tangential inlet, and a member closing the opposite end of said chamber from said axial inlet, said member having a conical wall portion converging from the wall of said chamber and having a diverging conical outlet orifice leading from said converging wall portion.

9. A spray nozzle of the class described having a body, a chamber within said body having a cylindrical wall, an axial inlet adjacent one end of said chamber, a discharge orifice leading from the opposite end of said chamber, a flow-balancing groove in the wall of said chamber arcuate in cross-section and extending around said wall for at least 180° of the circumference thereof, a tangential inlet leading into said chamber at one end of said groove, a liquid passageway in said body leading to said tangential inlet, a diversion passageway leading from a wall of said liquid passageway and extending transversely of the longitudinal axis thereof, said diversion passageway communicating with said axial inlet and being so constructed and arranged as to supply liquid thereto at a pressure lower than the pressure of liquid supplied through said tangential inlet, and a member threaded in the opposite end of said chamber from said axial inlet, said member having an inner converging conical wall portion leading to and communicating with a diverging conical outlet orifice in longitudinal alignment with said axial inlet.

10. A spray nozzle of the class described having a body, a chamber therein having a cylindrical wall, an outlet orifice from one end of said chamber in axial alignment with the center thereof, a liquid inlet passageway in said body

leading to said chamber and discharging thereinto tangentially of said wall, a second inlet passageway to said chamber discharging into the opposite end thereof from said outlet orifice in axial alignment therewith, a diversion passageway in said body leading from said first inlet passageway to said second inlet passageway and diverting liquid from said first liquid passageway by the static pressure of the liquid flowing through said first liquid passageway, and said first liquid passageway having a reduction in cross-sectional area adjacent the wall of said chamber forming a shoulder facing the flow of liquid through said passageway, and increasing the pressure on the upstream side of said shoulder, with a resultant increase in volume of the liquid entering said chamber through said axial inlet.

11. In a spray nozzle of the class described, a body, a chamber therein having a cylindrical wall, a liquid passageway in said body leading into said chamber through said wall, a flow balancing groove recessed in said wall substantially conforming in cross-section to a portion of the cross-sectional area of said inlet and extending around said wall for a portion of the circumference thereof and forming a partial continuation of said inlet, an outlet orifice from one end of said chamber in axial alignment with the center thereof, an axial inlet to said chamber in axial alignment with said outlet orifice, a liquid diversion passageway leading from said liquid passageway to said axial inlet, and said liquid passageway being of a reduced cross-sectional area adjacent said wall of said chamber on the downstream side of the point where said diversion passageway leads from said first liquid passageway, said portion of reduced cross-sectional area forming a shoulder facing the flow of liquid through said passageway and increasing the pressure and volume of liquid discharged through said axial inlet.

12. In a spray nozzle of the class described, a body, a chamber within said body having a cylin-

drical wall, an inlet to said body and entering said chamber tangentially along said wall, a flow balancing groove recessed in said wall and forming a partial continuation of said inlet substantially conforming in cross-section to a portion of the cross-sectional area of said inlet and extending along said wall to the side of said chamber opposite said inlet and conducting a portion of the liquid entering said chamber from said inlet along the cylindrical wall of said chamber in the form of a stream, and then projecting it into said chamber at the side thereof opposite said inlet and balancing the flow of liquid into said chamber along said wall, an axial inlet to one end of said chamber, a liquid diversion passageway leading from a wall of said first inlet passageway and communicating with said axial inlet for supplying liquid to said chamber through said axial inlet at a pressure lower than the pressure of the liquid supplied through said first inlet, and an outlet orifice from the end of said chamber opposite said axial inlet.
